UNITED STATES PATENT OFFICE.

PAUL G. ZIMMERMANN, OF KEYPORT, NEW JERSEY, ASSIGNOR TO AEROMARINE PLANE & MOTOR COMPANY, OF NEW YORK, N. Y., A CORPORATION OF NEW YORK.

HYDROAEROPLANE.

Application filed October 25, 1921, Serial No. 510,279. Renewed March 11, 1926.

This invention relates to hydroaeroplanes, and more particularly to that type of hydroaeroplane capable of making a landing on land or on the deck of a vessel. The objects 5 of this invention are to provide a craft having a great range of forward and downward vision, a great range of gun-fire, and at the same time maintain a low center of gravity, important for landing on a vessel, together 10 with a maximum of seaworthiness.

These objects are attained by a novel structure and combination of elements described in the annexed specification and illustrated in the drawings forming a part 15 hereof.

In said drawings:

Fig. 1 is a side elevation;
Fig. 2 is a front elevation; and
Fig. 3 is a top plan view.

20 A portion of the wings and outrigger are broken away in the various views to more clearly illustrate the embodiment of the invention.

The drawings illustrate a monoplane having 25 right- and left-hand wing portions 1 and 2 and a center wing portion 3, in which, at the front, is mounted a motor 4 having secured thereto a forward propeller 5. Mounted beneath the wing is a nacelle 6, such mounting being accomplished by means 30 of suitable struts and braces, some of which are marked *a*.

Carried by and beneath the wing of the plane, and at a short distance below, and at 35 opposite sides of, the nacelle, are right and left pontoons 7 and 8 having struts and braces, some of which are marked *b*, connecting with the nacelle in a suitable manner, apparent to those skilled in the art, so 40 as to cause the pontoons to be carried by the plane and nacelle in flight and to assume the weight of the entire plane when alighting. The plane is provided with a tail 9 and tail elevator 10, the tail being the usual 45 form and having a rudder portion 11 suit-

ably mounted, the entire tail and elevator being carried on an outrigger from the wing and pontoons, or intermediate bracing, such outrigger comprising members 12, 13, 14 and 15, suitably braced and guyed to form a 50 rigid and strong structure.

The plane is also provided with a tail skid 16, and with landing wheels 17 and 18, which latter are adapted to be got out of the way when alighting on the water, in the particular form illustrated being adapted to be folded into the pontoons, which have isolated receiving sections formed by fore and aft walls 19 and 20, together with bottom door portions 22 and 23 capable of closing. 55

By virtue of the general construction, the machine has a very low center of gravity in relation to the landing gear or the pontoons. This is very desirable when the hydroaeroplane is to make a landing on board a vessel, or on land, as it prevents disastrous forward tipping. 65

Referring to Fig. 3, the pilot seat is illustrated at 24 and it can be clearly seen that the pilot has an unobstructed downward and forward view between the sides of the nacelle and the pontoons, as well as a clear view in other directions. 70

The gunner's seat illustrated at 25, and the gun and gun mounting at 26, show the wide firing range without any obstructions except such small obstructions as the lower end of the rudder 11 and the two vertical struts 27. 75

What I claim as new is:

In a hydroaeroplane, the combination with the wing, of a motor mounted in the wing and a tractor propeller driven by the motor, a pair of side floats which together support the machine in the water, a nacelle mounted beneath the wing and somewhat above the floats so as to be out of the water, and an outrigger tail supported from the floats and the wing. 85

PAUL G. ZIMMERMANN.
